UNITED STATES PATENT OFFICE

148,255

DESIGN FOR A SEAPLANE FLOAT

Frank M. Salisbury, Kenmore, N. Y., assignor to
Frontier Aircraft Corp., Kenmore, N. Y.

Application December 14, 1945, Serial No. 124,742

Term of patent 7 years

(CL. D71—1)

To all whom it may concern:

Be it known that I, Frank M. Salisbury, a citizen of the United States, residing at Kenmore, in the county of Erie and State of New York, have invented a new, original, and ornamental Design for Seaplane Float, of which the following is a specification, reference being had to the accompanying drawings, forming part thereof.

Fig. 1 is a top plan view of a seaplane float showing my novel design;

Fig. 2 is a front end elevational view thereof;

Fig. 3 is a side elevational view thereof;

Fig. 4 is a rear end elevational view thereof; and

Fig. 5 is a perspective view of the seaplane float shown in Figs. 1-4.

The dot-and-dash line showing in the several

drawing figures is for illustrative purposes only.

I claim:

The ornamental design for a seaplane float, as shown and described.

FRANK M. SALISBURY.
